UNITED STATES PATENT OFFICE.

WILLIAM M. KELLY, OF NEW YORK, N. Y., ASSIGNOR TO AMERICAN TYPE FOUNDRERS COMPANY, OF JERSEY CITY, NEW JERSEY, A CORPORATION OF NEW JERSEY.

PRINTING-PRESS.

1,096,036.

Specification of Letters Patent. Patented May 12, 1914.

Application filed March 28, 1913, Serial No. 757,469. Renewed February 20, 1914. Serial No. 820,048.

To all whom it may concern:

Be it known that I, WILLIAM M. KELLY, a citizen of the United States, residing at New York, in the county and State of New York, have invented certain new and useful Improvements in Printing-Presses, of which the following is a specification.

This invention relates to printing presses of the type having a reciprocating bed and an impression cylinder movable toward and from the bed and more particularly to the means for actuating the bed and the means for raising and lowering the cylinder.

Among the objects of the invention are to provide a driving mechanism for the bed which will impart to it a uniform and relatively slow movement during the impression stroke and an accelerated movement on the reverse or return stroke; to provide means for insuring exactness of register between the bed and impression cylinder during the printing stroke; and to provide manual control of the movement of the cylinder toward and from the bed so that the cylinder may be instantly moved away from the bed at any point in the travel of the bed in either direction.

My improvements permit the cylinder to be geared or interlocked in registering relation with the bed during a larger part of the printing stroke than has heretofore been practicable in presses of this type.

Other novel features of the invention will be described in the following specification taken in connection with the accompanying drawings, in which:

Figure 1 is a side elevation of a printing press embodying my improvements. Fig. 2 is a longitudinal section thereof on the line 2—2 of Fig. 3. Fig. 3 is a transverse section through the bed operating mechanism. Fig. 4 is an enlarged elevation of a portion of the opposite side of the press from that shown in Fig. 1. Fig. 5 is a fragmentary vertical section through one of the bearings for the impression cylinder. Fig. 6 is a detail section on the line 6—6 of Fig. 4.

Referring to the drawings, 10 indicates the frame of the printing press and 11 the reciprocating type bed. The frame 10 has secured to the top thereof a guide and support 12 for the bed 11, this guide being engaged by bearing surfaces on the racks 13 and 14 carried by the bed. The frame 10 also carries the usual air buffers 15 to ab-

sorb shock in reversing the bed at the ends of its movements.

The frame 10 carries a bearing 16 in which is arranged the main driving shaft 17, this shaft having mounted on the inner end thereof the gear wheel 18. A driving shaft 19 is journaled in bearings in the frame 10 and may be driven from any suitable source of power. The shaft 19 carries, within the frame 10, a gear 20 which meshes with a gear 21 on a countershaft 22, the countershaft 22 being journaled in bearings in the frame 10 and carrying a gear 23 outside the frame which meshes with an idler gear 24 arranged on a shaft 25. The usual impression cylinder, which may be of any preferred construction, is arranged on a shaft 26 above the bed 11 and is driven by means of a gear 27 which meshes with the gear 24.

It will be observed from Fig. 3 that the gear wheel 18 has a comparatively broad face and that one side of the face of the gear is engaged by the rack 14. The opposite side of the face of the gear 18 is engaged by the gear 21 for the purpose of driving the gear 18. The shaft 19 is, in the operation of the machine, rotated continuously and at a uniform speed and consequently the gear 18 will also be driven at a uniform speed. On account of the reciprocation of the bed 11 it will be obvious that means must be provided for having the rack 14 out of engagement with the gear 18 at the ends of the movement of the bed and also during the reverse or non-printing stroke of the bed, on which stroke the bed will be moving in the opposite direction to the top of the gear wheel 18. This is accomplished by omitting the teeth for a portion of the circumference from that side of the gear 18 which is engaged by the rack 14. This omission of the teeth is indicated at the bottom of the gear 18, as shown in Fig. 3.

The frame 10 carries a guide 28 in the lower part thereof directly below the guide 12 and a frame 29 is arranged to slide between the guides 12 and 28. The frame 29 carries a stub shaft 30, on which is mounted a gear wheel 31, this gear wheel meshing with the rack 13 on the bed 11 and also with a rack 32 secured to the guide 28. For the purpose of clearness the gear 31 is shown in dotted lines in Fig. 2, but it will be obvious from this figure that any movement of the

frame 29 along its guides, in either direction, will effect a movement of the bed 11 in the same direction, but of double the extent of the movement of the frame. In the operation of the press the gear 31 always remains in engagement with the racks 13 and 32 and the frame 29 is moved in such a manner as to effect the desired movements of the bed 11. For the purpose of moving the frame 29 I have arranged in the web of the gear 18 a radial slot, in which slides a block 33, this block carrying a shaft 34 on which is rotatably mounted a block 35. The block 35 is arranged in the vertical slot 36 in the frame 29, and thus the shaft 34 forms a driving connection between the gear 18 and the frame 29. The slot 36 is at right angles to the guides 12 and 28.

Owing to the fact that the gear 18, which has a constant speed of rotation, and the gear 31 have driving connection with the bed 11, through the racks 13 and 14, during the printing stroke of the bed, it will be obvious that it is necessary to move the frame 29 during this stroke of the bed in such a manner that the peripheral speed of the gear 31 will be exactly the same as that of the gear 18. I accomplish this by means of a face cam 37, having a cam slot 38 therein, and a cam roller 39 arranged in this cam slot and rotatably mounted on an extension of the shaft 34 (see Fig. 3). As will be observed from Fig. 2 approximately one-half of the cam slot 38 is concentric with the axis of the shaft 17 and the other half is of varying curvature and the different portions thereof are arranged at different distances from the axis of the shaft 17 so that as the gear 18 rotates the shaft 34 will be at a uniform distance from the shaft 17 while traversing the lower half of the cam slot 38 and will, as a consequence, give a simple harmonic motion to the frame 29. While the roller 39 is traversing the upper part of the cam slot 38 the distance of the shaft 34 from the axis of the shaft 17 will vary and consequently the velocity imparted to the frame 29 will be in accordance with this varying distance. I have so designed the upper part of the cam slot 38 that the frame 29 will move at a uniform velocity while the roller 39 is traversing this part of the slot and therefore the gear 31 will also travel at a uniform velocity and this gear and the gear 18 will coöperate to give to the bed 11 the requisite uniform motion on the printing stroke. While the frame 29 is at the ends of its stroke and also while the roller 39 is traversing the lower half of the cam slot 38 the gear 18 is out of engagement with the rack 14 on account of a portion of the teeth being omitted from the gear 18, as hereinabove described. The gear 31 therefore drives the bed on the reverse or non-printing stroke and the gears 18 and 31 coöperate

to drive the bed throughout the printing stroke and since the racks 13 and 14 are on opposite sides of the center of the bed it will be seen that a uniformly acting propelling force will be applied to the bed on the printing stroke.

The impression cylinder rotates at a uniform speed and makes two revolutions for each reciprocation of the bed. In order to raise the impression cylinder so that the type will not engage the surface thereof during the reverse movement of the bed, the shaft 26 is arranged in bearings 40 which are vertically movable in the brackets 41. Screws 42 are adjustably arranged in the brackets 41 and carry sleeves 43 which are adjustable thereon and form abutments for springs 44 which bear against the under side of the bearings 40 and tend to move the latter upwardly. Arranged above the bearings 40 are the cross bars 45 which are connected with lower cross bars 46 by means of bolts or rods 47. The usual toggles 48 are provided between the lower ends of the screws 42 and the lower cross bars 46 so that when these toggles are in the straightened position shown in Fig. 4 the impression cylinder is drawn down into the printing position and when the toggles are in the open position shown in Fig. 1 the springs 44 are permitted to raise the impression cylinder to a position where it will not be engaged by the type.

For the purpose of automatically actuating the toggles 48 I have provided on the shaft 17 exteriorly of the frame 10 a cam plate 49, which is shown in dotted lines in Fig. 4. An arm 50 arranged on the pivot 51, secured to the frame 10, carries a cam roller 52 which traverses a suitable slot 53 in the cam plate 49 and this arm will be rocked on the pivot 51 as the shaft 17 rotates. A shaft 54 is mounted in suitable bearings in the frame 10 and carries a lever 55 on one end thereof. The lever 55 has arranged at its lower end a pin 56 adapted to be engaged by a hook 57 on the link 58 which is connected with the arm 50 by a pivot pin 59. The upper end of the lever 55 carries a pivot 60 which is connected with the pivot 61 of the toggles 48 by means of a link 62. The opposite end of the shaft 54 carries an arm 63 which is similarly connected with the adjacent toggles 48 by means of a link 64.

As will be seen from Fig. 4 the rotation of the shaft 17 causes the arm 50 to be rocked back and forth and so long as the hook 57 is in engagement with the pin 56 the toggles will be uniformly opened and closed in accordance with the movements of the bed 11. It is sometimes desirable, as for example when the impression cylinder is not provided with a sheet of paper, to have the impression cylinder in the raised position during the printing stroke and I have therefore

provided means which is adapted to be actuated by the foot of the operator of the press to accomplish this result. This means consists of a lever 65 which is pivoted to the frame 10 at 66 and has connected therewith a link or rod 67, the latter being attached to any suitable pedal mechanism whereby the rod can be moved up and down by the foot of the operator. Such pedal mechanisms are very common in machine construction and an illustration and description of the same is deemed unnecessary for the purposes of this application. The lever 65 carries a pin 68 which, as shown in Fig. 4, contacts with the lower surface of the end portion of the link 58 so that when the rod 67 is drawn downwardly the pin 68 will be raised and lift the hook 57 out of engagement with the pin 56. It will be observed that the lever 65 is provided with a projection 69 adjacent the pin 68 and this projection is adapted to engage the lever 55 and thus rock the lever 55 to open the toggles 48. The hook 57 has a downward projection 70 which will engage the pin 56 and open the toggles 48 on the next return stroke of the bed, in case the operator does not draw the rod 67 downwardly far enough to effect an opening of the toggles by the engagement of the projection 69 with the pin 56, as above described. It will thus be seen that I have provided a simple mechanism for opening the toggles in case of an emergency, and since both toggles are actuated by a single hook 57 there will be no liability of having one toggle open while the other is closed.

For the purpose of having an exact registration and uniform movement of the impression cylinder and the bed 11 during the printing stroke I have provided on the shaft 26 a mutilated gear 71, the teeth of which engage the teeth of the rack 72 on the bed 11 during the printing stroke and the blank portion of which is adjacent the rack during the reverse stroke of the bed. The up and down movements of the impression cylinder are very slight and therefore the gears 24 and 27, by means of which the shaft 26 is driven, always remain in mesh. It will be seen that during the printing movement the bed is in mesh with both gears 18 and 31 through the racks 14 and 13 on its under side and with the mutilated gear 71 on the impression cylinder through rack 72 on its upper side, thus insuring uniform movement of the bed and impression cylinder and also exactness of register between them.

Having thus described the invention what is claimed as new is:

1. In a printing press, the combination of a reciprocating bed, a plurality of racks thereon, a constantly rotating gear having a fixed axis and adapted to engage one of said racks on one of the strokes of the bed, a shaft movable in a plane parallel with the bed, a

gear mounted on said shaft and engaging another of said racks throughout both of the strokes of the bed, means for rotating said first-mentioned gear, and means for giving to said shaft and the gear thereon a reciprocating movement. 70

2. In a printing press, the combination of a reciprocating bed, a plurality of racks thereon, a constantly rotating gear engaging one of said racks on one of the strokes of the bed, a shaft adapted to reciprocate in a plane parallel with the bed, a gear on said shaft continuously engaging another of said racks, a fixed rack engaging said last-mentioned gear, and means for moving said shaft, when said first-mentioned gear is in engagement with its rack, at a velocity one-half the peripheral velocity of said gear. 75 80

3. In a printing press, the combination of a reciprocating bed, a plurality of racks thereon, a fixed rack parallel with one of the racks on the bed, a gear arranged between and continuously engaging the fixed rack and the rack on the bed which is parallel therewith, a gear wheel adapted to engage another of said racks, and means whereby said first-mentioned gear is reciprocated by said second-mentioned gear. 85 90

4. In a printing press, the combination of a frame, a reciprocating bed thereon, a plurality of racks on said bed, a guide carried by said frame, a member adapted to reciprocate on said guide, a gear wheel carried by said member and continuously engaging one of said racks, a second gear wheel adapted to intermittently engage another of said racks, and means whereby said member is reciprocated by said second gear wheel. 95 100

5. In a printing press, the combination of a frame, a reciprocating bed thereon, a stationary guide on said frame, a member adapted to reciprocate on said guide, means forming a driving connection at all times between said member and the bed, a constantly rotating wheel having a radially extending slot therein, means movable in said slot and connected with said member to form a driving connection between said wheel and said member, and means for moving said last-mentioned means in said slot 105 110 so as to give a uniform velocity to said member throughout the greater portion of one of the strokes thereof.

6. In a printing press, the combination of a frame, a reciprocating bed thereon, a stationary guide on said frame, a member adapted to reciprocate on said guide, means forming a driving connection at all times between said member and the bed, a constantly rotating wheel having a radially extending slot therein, means movable in said slot and connected with said member to form a driving connection between said wheel and said member, and a fixed cam member coöperating with said last-men- 120 125 130

tioned means to move the latter in said slot so as to give a uniform velocity to said member through the greater portion of one of the strokes thereof.

- 5 7. In a printing press, the combination of a frame, a reciprocating bed thereon, a stationary guide on the frame, a member movable on said guide parallel with the bed and having a slot at right angles to the guide, 10 means forming a driving connection at all times between said member and the bed, a constantly rotating wheel having a radial slot therein, means movable in the slots in said wheel and said member and adapted 15 to form a driving connection between the wheel and member, and means for moving said last-mentioned means in the slot in said wheel so as to give to said member a uniform velocity throughout the greater portion 20 of one of the strokes thereof.

8. In a printing press, the combination of a frame, a reciprocating bed thereon, a stationary guide on the frame, a member movable on said guide parallel with the bed and 25 having a slot at right angles to the guide, means forming a driving connection at all times between said member and the bed, a constantly rotating wheel having a radial slot therein, means movable in the slots in said wheel and said member and adapted to 30 form a driving connection between the wheel and member, and a stationary cam coöperating with said means to move the latter in the slot in said wheel so as to cause said bed 35 to be moved at a uniform velocity throughout the greater portion of one of its strokes.

9. In a printing press, the combination of a frame, a reciprocating bed thereon, a guide on the frame, a fixed rack, a rack on

said bed, a member movable on said guide 40 parallel with the bed, a gear wheel carried by said member and engaging said fixed rack and the rack on the bed, a constantly 45 rotating wheel having a radial slot therein, means movable in said slot and adapted to form a driving connection between the gear and said member, and means for moving said last-mentioned means in said slot so as to drive said bed at a uniform velocity throughout the greater portion of one of its 50 strokes.

10. In a printing press, the combination of a frame, a reciprocating bed thereon, a plurality of racks on the bed, a fixed rack carried by the frame, a guide on the frame, a member slideable on said guide, a gear wheel carried by said member engaging said fixed rack and one of the racks on the bed, a constantly 55 rotating gear wheel adapted to engage another of the racks on the bed during one of the strokes of the bed and having a radial slot therein, means movable in said slot and forming a driving connection between said last-mentioned gear wheel and said member, and a fixed cam for moving 60 said last-mentioned means in said slot so as to give to said member a uniform velocity equal to one-half the peripheral velocity of said second-mentioned gear wheel while the latter is in engagement with the rack on 65 the bed.

In testimony whereof I affix my signature in presence of two witnesses.

WILLIAM M. KELLY.
